(57) **CLAIM**

The ornamental design for a textile including surface ornamentation, as shown and described.

DESCRIPTION

The patent or application file contains at least one drawing executed in color. Copies of this patent or patent application publication with color drawing(s) will be provided by the Office upon request and payment of the necessary fee.

The sole FIGURE is a top view of the textile including surface ornamentation showing my new design.

The broken line perimeter depicts the boundaries of the claim and forms no part thereof.
